UNITED STATES PATENT OFFICE.

GEORGE JUSTIN ADAMS, OF BROOKLYN, NEW YORK, ASSIGNOR TO COLGATE & COMPANY, OF NEW YORK, N. Y.

BOTTLE-CLOSURE.

SPECIFICATION forming part of Letters Patent No. 714,991, dated December 2, 1902.

Application filed June 11, 1902. Serial No. 111,130. (No model.)

To all whom it may concern:

Be it known that I, GEORGE JUSTIN ADAMS, a citizen of the United States, and a resident of the city of New York, borough of Brooklyn, in the county of Kings and State of New York, have invented a new and Improved Bottle-Closure, of which the following is a full, clear, and exact description.

This invention relates to improvements in closures for bottles and similar packing devices for containing tooth-powder or other toilet preparations, the object being to provide a closure comprising two capped members provided with openings designed to register upon turning one cap relatively to the other, the tops of the caps being resilient or spring-yielding, so as to maintain a close connection when the movable cap is turned, thus preventing the accumulation of powder between the top plates of the caps.

A further object is to provide a simple means for limiting the rotary movement of the movable cap when in use, but permitting its removal when desired.

25 I will describe a bottle-closure embodying my invention and then point out the novel features in the appended claims.

Reference is to be had to the accompanying drawings, forming a part of this specification, 30 in which similar characters of reference indicate corresponding parts in all the figures.

Figure 1 is a perspective view of a bottle with a closure embodying my invention applied thereto. Fig. 2 is a vertical section of 35 the closure. Figs. 3 and 4 are plan views showing the parts of the closure in different positions, and Fig. 5 is a plan view of the fixed cap.

The closure comprises a fixed cap 1, a portion of which is screw-threaded, and on the lower portion of the cap is an outwardly-extended flange 2, which engages on the upper portion of the bottle, as seen in Fig. 1. A movable cap 3 has screw-threaded engagement with the fixed cap, as clearly indicated in Fig. 2. The top plate of the fixed cap is provided with an outlet-opening 4, and the top plate of the rotary cap is provided with an outlet-opening 5. These openings are designed to be placed in register for the purpose of discharging the powder. When, however, no powder is to be discharged, the openings are to be placed out of register by rotating the cap 3.

As a means for limiting the rotary movement of the cap 3 I provide its top plate with a downwardly-extending lug 6, designed to engage in a segmental channel 7, formed in the top of the fixed cap. When placing the cap 3 on the fixed cap, when the movable cap reaches nearly to its lowermost position and the lug 6 is engaging on the upper surface of the fixed cap the said upper surface will spring downward slightly until the lug passes into the channel 7. When the lug passes into the channel, of course the top plate of the fixed cap will spring upward against the inner side of the top plate of the rotary cap. Upon rotating the cap 3 until the lug engages against the end of the channel 7 the opening 5 will be placed in register with the opening 4. By a reverse movement the opening 5 will be moved out of register with the opening 4, and the lower edge of the cap 3 engaging with the flange 2 will prevent the said rotary cap from moving too far in this last-named direction.

During the movement of the rotary cap the top plates of the two caps will be held close together, so as to prevent powder from getting between them.

Having thus described my invention, I claim as new and desire to secure by Letters Patent—

1. A bottle-closure comprising a fixed cap 85 having a spring-yielding top plate provided with an opening and with an arc channel, and a cap mounted to rotate on the first-named cap, having a spring-yielding top provided with an opening and an inwardly-extending 90 lug for engagement in said channel.

2. A bottle-closure comprising a fixed cap having a threaded portion and a spring-yielding top plate provided with an opening and an arc channel, and a cap having a screw-threaded portion engaging with the thread of the fixed cap, the said last-named cap having a spring-yielding top plate provided with an opening and an inwardly-extended lug for engaging in said channel.

In testimony whereof I have signed my name to this specification in the presence of two subscribing witnesses.

GEORGE JUSTIN ADAMS.
